UNITED STATES PATENT OFFICE.

HERMAN E. S. CHAYES AND AUGUST P. JURGENSEN, OF NEW YORK, N. Y., ASSIGNEES,
BY MESNE ASSIGNMENTS, TO CHAYES DENTAL INSTRUMENT CORPORATION, OF
NEW YORK, N. Y., A CORPORATION OF DELAWARE.

DENTAL INSTRUMENT.

Application filed September 4, 1924. Serial No. 735,847.

This invention relates to the construction of dental drill heads.

A general object of the invention is to provide a dental drill head or hand-piece in which improvements are incorporated throughout the entire organization of structure.

A feature of the invention is the provision of a spindle construction in which the spindle parts and tool held thereby are brought into mutual axial alignment in the act of bringing the chuck into gripping relation with the shank of the tool.

Another feature of the invention resides in a constructional arrangement which provides for disassembling the device without the use of tools.

Another feature of the invention resides in a constructional arrangement which provides for assembling the device without the use of tools.

Another feature resides in the use of a driving pulley provided with a protective sleeve for normally enclosing and guarding a bearing adjusting device.

Another feature resides in the use of an all-metal construction to provide for the complete sterilization of the device.

Another feature resides in the provision of bearings for the spindle located adjacent the extreme end portions thereof in order to provide the most effective support for the spindle when in rotation.

Another feature includes a unitary structural formation of the hand piece the greater portion of which is formed of lightweight metal whereby a desirable lightness in weight is achieved.

Still another feature resides in the provision of a removable chuck member which is readily extractable from the spindle housing at the rearmost end thereof.

Still other features of the invention will be hereinafter referred to.

In the drawings, in which a preferred embodiment of the invention has been selected for illustration,

Figure 1 is a view in longitudinal section of a dental drill head embodying the invention.

Figure 2 is a view in side elevation and on a reduced scale of the device shown in Figure 1.

Figure 3 is a view in cross-section taken on the line 3—3 of Figure 1.

Figure 4 is a view in cross-section taken on the line 4—4 of Figure 1.

Figure 5 is a longitudinal sectional view showing in detail the construction of spindle and chuck parts with a tool held in place in the chuck.

Figures 6 and 7 are views similar to Figure 5 showing further details of construction.

Figure 8 is a view in cross-section taken on the line 8—8 of Figure 5.

Figure 9 is a view similar to Figure 5 showing the bearing support for the spindle.

Figure 10 is a sectional view on an enlarged scale showing a detail of construction.

Figure 11 is a view in side elevation of the parts shown in Figure 10.

Figure 12 is a view in cross-section taken on the line 12—12 of Figure 10.

Referring to the drawings for a more detailed description of the invention, in Figures 1 and 2 a dental drill head or hand piece is shown which includes an elongated one-piece cylindrical casing 10 having a grooved and knurled portion 11 which facilitates the firm holding of the drill head in the hand of the operator. The cylindrical casing member 10 is provided at its forward end with a tapering end section 12 formed of stainless steel or the like and arranged to serve as a bearing member in which the forward end of the spindle structure is journaled. The bearing member 12 is seated in a screw-threaded relation in the forward end of the casing 10 as at 13.

The cylindrical casing member 10 is preferably formed of duralumin or some other metal of metal alloy having a relatively light weight characteristic. The rearward end of the casing 10 is fitted with a sleeve 14 formed of bronze or the like having a drive fit with said casing and adapted to serve as a journal having a swiveled relation with an angular bracket member 15 which is in 100

turn swiveled on a supporting shaft 16 extending at right angles to the axis of the casing 10.

The rearward end of the casing 10 is 5 screw-threaded as at 16^a to receive a bearing bushing 17 which may be longitudinally adjusted in its seat in the end of the casing 10 by reason of the screw-threaded relation referred to. In order to lock the bearing bushing 17 in a desired adjusted position a lock nut 18 carried by the bushing 17 on a section 10 thereof which protrudes from the end of the casing 10 is adapted to bear against the adjacent ends of the casing 10, bronze sleeve 14, 15 and an end of the bracket member 15. By this arrangement the lock nut 18 serves not only to hold the bearing bushing 17 in its adjusted position but the lock nut also holds the swiveled parts 14 and 15 in their operable 20 relation, the other end of the engaged portion of the bracket member bearing against a shoulder 19 formed for the purpose on the bronze sleeve 14.

The bearing bushing 17 forms a bearing 25 for the sleeve 20 which is driven tightly onto a hollow spindle member 21 so that the spindle member 21 is free to rotate within the bearing bushing 17. The forward end of the hollow spindle member 21 is provided 30 with an extended journal piece 22 which is journaled in the bearing member 12 already referred to. The hollow spindle member 21 is thereby provided with bearing supports at, or substantially at, its opposite extremities.

In order to rotate the hollow spindle 21 within the casing 10, a pulley 23 is mounted 40 on the spindle 21 so as to rotate the same when the pulley itself is rotated. It will be seen that the position of the pulley 23 is adjacent the rearmost extremity of the casing 10 and that an axially extending hollow flange member 24 projects from the forward face of the pulley 23 into guarding or protecting relation to the lock nut 18 and the finger piece 25 by which the bearing bushing 17 is adjusted in its seat. With this structural arrangement the adjusting members 18 and 25 are protected from accidental movement 45 by the hands of the operator. On the other hand the covering up of these normally exposed members prevents injury that might otherwise occur to the hands of the operator using the device. The hand piece is through 50 this arrangement left wholly free from obstructing parts from the forward edge of the pulley flange member 24 to the extreme tip portion of the casing 10.

An important feature of the invention 55 resides in the construction of the spindle by which the tool shafts are held in place in the device. This construction includes a longitudinally adjustable shaft or core member 27 which has a screw-threaded relation 60 with the rearmost extremity of the hollow

spindle member 21 as at 28 and extends forwardly into the hollow spindle member 21 to a position within the rear portion of the journal piece 22 carried by the end of hollow spindle member 21. The forward extremity 70 of the shaft 27 is hollowed out as at 29 to receive the end of the shaft 30 of a drill or other tool. The extreme forward portion of the hollow end of the shaft 27 is arranged to engage the rearmost end of a hollow chuck 75 member 32 which is longitudinally slit inwardly from its opposite ends for a portion of its length as at 33. The extremities of the chuck member 32 are beveled as is shown at 80 34 for engaging correspondingly beveled portions formed in the journal piece 22 and on the terminal portion of the shaft 27. The beveled engagement of these parts is such that pressure exerted against the chuck member 32 by the longitudinal movement of the 85 shaft 27 compresses or forces the flexible end portions of the chuck 32 inwardly against the tool shaft 30 which may be contained therein. It will be seen that the clamping action which is thus exerted by the chuck 90 member 32 against the contained shaft part 30 will hold the tool rigidly in its operating position. Not only is the tool held firmly in its operating position by the structural arrangement referred to, but the passing of 95 the tool shaft through the bearing member 12, the journal piece 22, the chuck 32, and to the hollowed-out portion 29 of the shaft 27, provides for the positive aligning of the tool shaft 30 with the axis of rotation of the 100 spindle. The result is that the tool is smoothly driven without lateral vibration so that effective work can be accomplished thereby.

The spindle member 21 is driven through a 105 pulley 23 mounted on the spindle by means of a split clamping flange 36 formed on the pulley and a nut 35 cooperating with said flange. The chuck is operated to clamp or release the drill by rotation of knurled finger 110 piece 37.

In addition to the operating of the chuck in the manner described, the entire inner spindle and chuck structure may be readily removed from their positions in the hollow 115 spindle member 21. This is accomplished by the simple withdrawal of the shaft 27 from its position in the hollow spindle member 21 by turning the threaded portion 28 of the shaft from its engagement with the inner end of the hollow spindle member 21. The shaft 27 may then be completely withdrawn from its position as will be clear whereupon the chuck member 32 will drop through the hollow member 21 and out 120 through the open end thereof.

The chuck member is as readily placed in position within the hollow member 21 by merely dropping it into the open bore of the hollow shaft 21 and placing the inner 130

shaft 27 in position. The inner shaft 27 will inevitably take its proper engaging position with the rearmost end of the chuck 32 because of the angular disposition of the 5 interengaging parts.

The supporting bracket member 15 is swiveled on the shaft 16 as has already been stated, the shaft 16 being seated in a pulley supporting member 40 on which the pulleys 10 41 are mounted in flanking relation thereto.

The position of the pulleys 41 is so related to that of the pulley 23 that a belt 42 passing around the pulleys 41 and over the pulley 23 extend to a suitable driving pulley not 15 shown.

A universal joint connection is thus provided which insures a proper driving position of the pulley 23 in any position in which the hand piece may be held. The pulley supporting member 40 has hinged 20

relation with a socket member 43 which receives the end of a stem not shown on a bracket arm carried by the power supplying device. The spindle member 15 is provided in the under portion thereof with an oil 25

receiving opening 44 which, when the parts are inverted, leads to a corresponding opening 45 passing through the sleeve 14 and the wall of the casing 10. By rotating the casing 10 in its seat in the bracket 15 until 30

aligned marks which may be provided are brought into proper position, oil dropped into the opening 44 will pass through the openings 45 into the annular channel 46 between the casing 10 and the rotatable 35

hollow spindle member 21. The oil having reached this chamber will find its way to all parts of the relatively moving portions of the spindle and casing structure.

It will be seen that the structure thus provided is relatively light in weight since all but the bearing or journal parts are formed 40 of light-weight metal. The all metal construction provides for the complete sterilization of the device. The unitary structure 45

of the entire length of the hand piece provides a simplified and improved construction. The simplified means for taking apart the construction without the use of tools is a valuable feature of the invention.

The device as a whole characterized by its 50 simplicity of construction and the facility which is provided for adjusting or assembling the parts.

What is claimed is:—

1. In a dental drill head, a cylindrical 55 casing having a spindle mounted therein, a bearing sleeve secured about said casing, a bracket rotatably supporting said bearing sleeve, an adjustable bearing mounted in one end of the casing, and a single means for 60 holding said bearing in adjusted position and for holding said casing in position in said bracket.

2. In a dental drill head, an all-metal cylindrical casing having a converging nose 65 piece at one end forming a bearing for a spindle, a bracket member in which the casing is swiveled adjacent the other end, a bearing bushing having a screw-threaded relation with the inner wall of the swiveled 70 end of the casing for longitudinal adjustment therein, said bushing projecting through the open end of the casing, a lock nut operating on the projecting end of the bushing and adapted to engage the end of the casing 75 and the bracket to lock the bushing in adjusted position and hold the casing in swiveled position in the bracket.

3. In a dental drill head, a cylindrical 80 casing formed of light-weight metal and having an extension tip member forming a bearing for a spindle, a bearing member mounted in longitudinally adjustable relation in the other end of the casing, a lock nut adapted to be received on the bearing 85 member and to be brought into locking engagement with the end of the casing, a spindle housed in said casing and journaled in said bearings, a pulley mounted on the spindle in driving relation thereto, and an 90 axially extending circular flange on the pulley arranged to serve as a guard for the lock nut and exposed end of the bearing.

In testimony whereof we affix our signatures.

HERMAN E. S. CHAYES.
